UNITED STATES PATENT OFFICE.

JOHN F. SETH, OF HELENA, MONTANA.

VALVE TOOL.

Application filed April 14, 1927. Serial No. 183,808.

This invention relates to improvements in valve tools and has as its general object to provide a tool which may be readily and quickly adapted for use in the grinding of the valves of internal combustion engines as well as for use in compressing the springs of such valves to permit of removal of the pins against which the spring washers rest under normal operating conditions of the engine, so that the valves may be removed by the use of the device.

It is a well known fact that in grinding valves it is desirable that a uniform pressure be exerted upon the valve head while it is being rotated back and forth during the grinding or facing operation and therefore it is one of the objects of the present invention to provide a tool by the use of which any desired degree of pressure may be imposed and maintained on an internal combustion engine valve while the tool is being operated to rotate the valve to effect grinding of the same to its seat.

Another important object of the invention is to provide a tool for this purpose embodying means adapting it to be anchored to the valve stem and valve and thus maintained in proper position with respect to the valve during the operation of the tool to effect grinding of the valve, thus overcoming the disadvantages which attend the use of valve grinding tools of ordinary construction.

Another object of the invention is to so construct the tool that it may be employed as a means for compressing the spring of a valve to permit of removal of the cross pin from the valve stem and thus permit of subsequent complete removal of the valve and spring, the construction of the tool being such that when actuated to compress the spring its parts will be automatically locked so that the tool may be, at this time, released while the pin is being removed, thus leaving the workman's hands free in performing this operation.

Another object of the invention is to so construct the tool that the same may be employed in connection with valves of various sizes and types without any alteration in the construction of the tool.

In the accompanying drawings:

Fig. 1 is a side elevation of the valve tool embodying the invention, the view illustrating the tool applied to a valve for the pur-

pose of grinding or refacing the valve and the parts being shown in operative position in full lines and in inactive position in broken lines;

Fig. 2 is a view in front elevation of the tool;

Fig. 3 is a horizontal sectional view taken substantially on the line 3—3 of Fig. 1 looking in the direction indicated by the arrows;

Fig. 4 is a similar view on the line 4—4 of Fig. 1 looking in the direction indicated by the arrows;

Fig. 5 is a view similar to Fig. 1 illustrating the tool adapted for use in the compression of a valve spring preparatory to removal of the valve and spring.

The tool comprises a body member which is indicated by the numeral 1 and which is rectangular in cross section, being straight throughout the greater portion of its length and of dimensions suitable for the purposes of the invention. At its lower end the body 1 is formed with an arm 2 which extends forwardly from the body and in a general downward direction and at its lower end is forked so as to provide spaced fingers 3 which are adapted to straddle the valve stem, indicated by the reference character S as shown in Figure 1 and engage beneath the washer W which is fitted upon the stem and against which the valve spring S' is adapted to bear, the upper end of the spring bearing beneath the overhanging portion of the engine block as usual so as to hold the valve head H to its seat. The reference letter P indicates the usual pin which is fitted through the valve stem and which supports the washer W. The fingers 3 are spaced apart a sufficient distance to adapt the forked end of the arm 2 to engage the valve stem S and prevent any displacement of the arm with respect to the stem after the arm has been arranged in the manner shown in Figure 2 and with the upper sides of the fingers engaging the under side of the washer W. At its upper end the body 1 is provided with an arcuate forwardly extending supporting portion or head 4 which occupies the same plane as the body 1 and the arm 2 and which is located above the said arm. A series of openings 5 is formed in the head 4, the series extending from the end of the head inwardly for a suitable distance so as to provide a desired number of the

openings, and a hand lever 6 is provided and includes spaced side members 7 which, at the forward end of the lever, straddle the forward portion of the head 4 and are pivotally suspended from the head through the medium of a pin 8 which is fitted through openings in the said ends of the portions 7 and interchangeably through the openings 5, the pin being preferably provided at one end with a head 9 and being retained against accidental withdrawal by means of a cotter pin 10 which is fitted through its other end portion. By reference to Figure 1 of the drawings it will be observed that the side members 7 of the lever 6 are formed with stems inwardly of their ends which are pivotally connected with the head 4, these stems being indicated by the numeral 11, and in providing these stems the side members 7 of the lever are so formed as to provide portions 12 which extend at approximately a right angle upwardly from the remaining portions of the said side members of the lever. It will be observed by reference to Figure 1 that the portions 12 of the hand lever are suspended substantially vertical and the other portions which are indicated by the numeral 13 extend approximately horizontally and rearwardly and straddle the upper portion of the body 1, being relatively braced at a point rearwardly of and spaced from the said body by a rivet 14. The spaced members 7 of the lever 6 are integrally connected at the rear ends of their portions 13 by an end piece 15 and the members are relatively offset as at 16 in an outward direction adjacent to the rivet 14 so that a handle 17 is provided at this end of the lever. It will now be evident that the lever is suspended from the head 4 for swinging movement about the pin 8 as a pivot, and the purpose of constructing and arranging the lever in the manner described will now be explained.

The numeral 18 indicates a supporting and bearing arm which is bifurcated at its rear end to provide spaced portions 19 which straddle the body 1 and through which portions and openings 20 formed in the body 1, is fitted a pivot pin 22, the pin being adapted to be fitted through the openings 20 interchangeably so that the arm 18 may be pivotally supported at various elevations. It will be observed by reference to Figures 2 and 3 of the drawings that the spaced members of the lever 6 straddle the arm 18 and the arm is formed with a longitudinally extending slot 23 through which and openings in the stems 11 of the side members 7 of the hand lever is fitted a pivot pin 24. It will now be evident that when the lever is elevated substantially as illustrated in broken lines in Figure 1, the pin 24 riding in the slot 23 will effect an upward swinging movement of the arm 18 whereas, on the other

hand, when the lever 6 is swung downwardly, the pin 24 will ride against the lower wall of the slot 23 and the arm will be swung downwardly about its pivot as shown in full lines in the said figures.

At its outer end the arm 18 is formed with a bearing sleeve 25 in which is rotatably mounted a shaft 26. A pin 27 is fitted through this shaft and engages the under side of the said sleeve 25 so that the shaft is prevented from sliding upwardly in the sleeve beyond a predetermined position which is that illustrated in Figure 1 of the drawings. The lower end of the shaft 26 is fitted into a socket provided in a cylindrical head 28 which is provided upon its under face with spaced lugs 29 designed to engage the usual notches or grooves formed in the upper side of the valve head H, the head 28 being held assembled with the lower end of the shaft by a pin 30 which is fitted diametrically through the head and the said lower end of the shaft. The upper end of the shaft 26 is preferably squared as indicated by the numeral 31 for a purpose which will now be made apparent. In practice, several of the heads 28 will be supplied with each valve tool and the heads will be of different diameters and have valve head engaging lugs of different sizes and differently spaced and, if desired, as shown in Figure 1, each head may be provided, in addition to the lugs 29 upon one face thereof, with lugs 32 formed upon its opposite face, the lugs 29 and the lugs 32 being differently spaced and of different sizes, thus providing for a wide range of choice in the use of a minimum number of the heads 28.

In order that rotary motion may be imparted to the shaft 26, means is provided which will now be described. The numeral 33 indicates an arm which is pivotally mounted at its rear end by means of a pivot pin 34, upon the head 4 at the upper side of the said head and substantially midway between the ends thereof, and this arm 33 extends forwardly from the head and is provided at its forward end with a bearing sleeve 35 in which is slidably and rotatably mounted a shaft 36, a crank handle 37 being fixed upon the upper end of the shaft and providing means whereby the shaft may be manually rotated. At its lower end the shaft 36 is provided with a head 38 having a squared socket 39 to fit the squared upper end 31 of the shaft 26 as illustrated in Figure 1 of the drawings.

From the foregoing description of this embodiment of the invention it will be understood that in the use of the same in grinding valves the lever 6 is to be first swung upwardly to substantially the broken line position shown in Figure 1, the pivot pins 8 and 22 having been previously adjusted in the openings 5 and 20 respectively in ac-

cordance with the engine, the valves of which are to be ground and likewise in accordance with the dimensions of the valves. The forked end 3 of the arm 2 is then engaged beneath the washer W upon the valve stem S, and the tool is positioned substantially upright and the lever 6 swung downwardly until the head 28 is properly engaged with the head H of the valve to be ground. In the meantime the shaft 36 has been slid upwardly in the bearing sleeve 35 so as to permit of movement of the squared upper end of the shaft 26 past the head 38 at the lower end of the said shaft 36, and after the shaft 26 has been adjusted in the manner stated so as to bring its head 28 into engagement with the valve head and with the said shaft in axial alignment with the valve stem, the shaft 36 is slid downwardly through the sleeve 35 and this adjustment of the shaft together with a downward swinging movement of the arm 33 will permit of the head 38 being engaged with the squared upper end of the shaft 26. A suitable degree of pressure may then be exerted in a downward direction upon the handle 17 of the lever 6 so as to exert pressure against the valve head H in a downward direction and inasmuch as downward movement of the lever 6 will effect, in a sense, an adjustment of the valve engaging head 28 and the forked end 3 of the arm 2 toward each other, it will be understood that the pressure exerted upon the lever will serve to maintain the tool steadily in upright position and assembled with the valve while the crank handle 37 is rotated backwardly and forwardly to effect corresponding rotation of the valve head and thus grind the same to its seat. It will be quite evident that the pressure exerted upon the valve head may be varied by a corresponding variation in the pressure exerted upon the lever 6.

It will be observed by reference to Figure 1 that in the use of the tool just described the pivot 24, in the extreme lowered position of the arm 18 and lever 6, is located in rear of a vertical line passing through the pivot 8, the pressure exerted upon the lever being only sufficient to insure of stability of the tool while being operated to grind the valve.

Figure 5 of the drawings illustrates the manner in which the tool is employed in compressing the valve spring so as to elevate the washer W and permit of withdrawal of the pin P and in this figure parts which correspond to those in Figures 1 to 4 inclusive are indicated by the same reference numerals inasmuch as the tool is identically the same tool with the exception that the pivot pin 34 has been withdrawn and the arm 33 and the shaft 36 supported thereby have been removed as these parts are not required when the tool is put to the use shown in the said Figure 5. By reference to the

said figure it will be observed that the pivot pin 22 has been removed and inserted through an opening more elevated than the opening in which it was engaged in Figure 1 although, under the conditions illustrated in Figure 5, the position of the pivot pin 8 is not required to be changed. In using the tool to compress the valve spring and permit of extraction of the pin P, the head 28 may be permitted to remain in place as shown in Figure 5 so as to conveniently adapt the lower end of the shaft 26 for engagement with the valve head H, or this head 28 may be removed from the shaft by withdrawal of the pin 30 and the lower end of the shaft may be brought into direct engagement with the valve head, this being a mere matter of choice and immaterial so far as operation of the tool is concerned. In any event, in using the tool as shown in Figure 5, the lever 6 is swung downwardly to substantially the full line position shown in the said figure, the parts having been first adjusted to the position shown in broken lines and the tool bodily shifted so as to bring the forked end of the arm 2 into engagement beneath the washer W and the head 28 into engagement with the head of the valve. The lever 6 is then swung downwardly as stated and as its downward movement is continued, the pivot pin 24 will ride in the slot 23 until it passes to a position forwardly of a vertical line intersecting the pivot pin 8 at which time the lever will be automatically locked in its lowered position and the spring S' will be compressed and the washer W elevated sufficiently far above the pin P to permit of ready extraction of the pin as clearly shown in broken lines, in the instance of the said washer and spring, and in full lines, in the instance of the forked end of the arm 2, in the said Figure 5. After the pin P has been withdrawn, the lever 6 may be swung upwardly so as to effect separation of the forked end 3 of the arm 2 and the head 28 from the washer W and valve head H thus permitting the valve and its stem to be bodily extracted and the spring S' to be removed.

From the foregoing description of the invention it will be seen that there is provided a tool which may be very conveniently adapted for use in either the grinding of the valves of internal combustion engines or in the compression of the valve springs so as to permit of removal of the valves and it will likewise be evident that when the tool is employed as shown in Figure 5 and the lever is adjusted to the full line position shown in the said figure and becomes locked, due to the passage of the pivot pin 24 past dead center, the tool may be released and will remain in its clamping adjustment while the pin P is being extracted.

It is to be understood, of course, that va- 130

rious changes may be made, within the scope of what is claimed, without departing from the spirit of the invention.

Having thus described the invention, what I claim is:

1. A valve tool of the class described comprising a body member having an arm at its lower end provided with means to straddle a valve stem and engage beneath the spring thereon, an arm pivotally mounted upon the body, valve head engaging means supported by the arm above and in opposed relation to the stem and spring engaging means of the arm, a lever pivotally mounted upon the body, and an element carried by the lever and slidably coacting with the arm to effect swinging adjustment thereof, in the movement of the lever, and thereby effect adjustment of the valve head engaging means into and out of active position, the pivot for the lever and the said element upon the lever which coacts with the arm being so relatively located as to effect locking of the lever when adjusted to the position in which the arm is held by the lever, with its valve head engaging means in active position.
2. A valve tool of the class described comprising a body member having an arm at its lower end provided with means to straddle a valve stem and engage beneath the spring thereon, an arm pivotally mounted upon the body, valve head engaging means supported by the arm above and in opposed relation to the stem and spring engaging means of the arm, the said arm having a longitudinal slot therein, a lever pivotally mounted upon the body, a pin carried by the lever and slidably engaging in the said slot whereby to operatively connect the lever with the arm to effect adjustment of the arm into and out of active position upon adjustment of the lever,

the pivot for the lever and the pin upon the arm being so relatively located that when the lever is in position to hold the arm active, the pin will be at that side of a vertical line 45 passing through the pivot for the lever opposite the side at which it is located when the lever is in position to hold the arm inactive.

3. A valve tool of the class described comprising a body member having an arm at its lower end provided with means to straddle a valve stem and engage beneath the spring thereon, an arm pivotally mounted upon the body, valve head engaging means supported 55 by the arm above and in opposed relation to the stem and spring engaging means of the arm, a lever pivotally mounted upon the body above the arm, the said arm having a longitudinal slot therein, a pin carried by 60 the lever and working in the slot and establishing operative connection between the lever and arm to effect swinging adjustment of the arm upon actuation of the lever, movement of the lever in one direction serving to 65 elevate the arm and lift the valve head engaging means to inactive position and movement of the lever in the opposite direction serving to lower the arm to move the valve head engaging means into active engagement 70 with the valve head, the pivot for the lever and the pin upon the arm being so relatively located that in the first mentioned position of the lever the pin will be at one side of a vertical line passing through the pivot for 75 the lever and, when the lever is in the other position, will be at the other side of said line to effect automatic locking of the lever in the last mentioned position.

In testimony whereof I affix my signature.

JOHN F. SETH.
